METHOD OF AND APPARATUS FOR TREAT-
ING HYDROCARBONSErik Mutter, New Brighton, N. Y., assignor to
Standard Oil Development Company, a corpo-
ration of Delaware

Application May 29, 1930, Serial No. 456,931

2 Claims. (Cl. 196—74)

This invention relates to the treatment of hydrocarbons with gaseous reagents to obtain chemically modified products. The invention will be fully understood from the following description taken in connection with the accompanying drawing in which latter the figure is a sectional view diagrammatic in character of a form of apparatus suitable for carrying out the invention.

- 10 Referring to the drawing reference numeral 1 designates a heating structure which is divided by walls 2 into a plurality of chambers 3, 4 and 5. Hot gases from a furnace are introduced into these chambers through line 6 and openings 7. 15 The hot gases are discharged from the chambers through openings 8 into a discharge stack 9. Containers 12, 13 and 14 are associated with the chambers 3, 4 and 5 and project downwardly thereinto. Cylindrical shells or tubes 15, 16 and 20 17 project downwardly from the containers 12, 13 and 14. These tubes are relatively long and of relatively small cross-sectional area. If desired, a plurality of the tubes can be connected to each container. A valved feed line 19 for hydrocarbons opens into the lower portion of tube 15. A discharge line 20, having a valve 21, communicates with the container 12 below the normal level of liquid therein and connects with the lower portion of the tube 16. A similar discharge line 22 having a valve 23, connects container 13 with tube 17. A discharge line 25 leads from the lower portion of container 14 and is provided with a valve 26.

35 Gaseous reagent is adapted to be injected into the lower portion of tubes 15, 16 and 17 from a line 27 through branch lines 28, 29 and 30. Valves 31, 32 and 33 are provided in these branch lines respectively. The gaseous reagent can be cold air, heated air, super-heated steam or other re- 40 action gas. The reagent is preferably injected under greater than atmospheric pressure.

The liquid level in the containers 12, 13 and 14 is controlled by means of floats 35, 36 and 37 respectively. Float 35 is operatively connected to 45 actuate valves 21 and 32 by means of a line 38. Raising of the liquid level in container 12 causes the float 35 to open valves 21 and 32. Float 36 of container 13 similarly actuates valves 23 and 50 33. Float 37 is operatively connected to a pump, not shown, through line 40 whereby the pump is actuated when the liquid level in container 14 rises above a predetermined position. The pump is connected with the discharge line 25.

55 Vapors accumulating in the vapor space of

container 12, 13 and 14 are withdrawn through a line 41 to a jet condenser 42. Cooling liquid such as water is introduced into the jet condenser through a line 43. The jet condenser communicates with a separator 44 containing baffles 60 45. The condensate and cooling liquid separate into layers in the separator and the condensate is withdrawn through a line 46. Exhaust steam or the like can be introduced into the vapor space of containers 12, 13 and 14, through a 65 valved line 47.

Treated hydrocarbons can be withdrawn after treatment in container 12 and tube 15 by means of a valved line 48. Similarly the hydrocarbons which have been treated additionally in container 70 13 and tube 16 can be withdrawn through a valved line 49.

By the construction described residual hydrocarbons are lifted by means of a current of gaseous reagents so as to effect circulation of the 75 hydrocarbons through the system. At the same time intimate contact is effected between the gaseous reagent and the hydrocarbons to facilitate the reaction there between. As a result oxidized asphalts are produced continuously, 80 the consumption of gaseous reagent is reduced to a minimum and at the same time no extra pumping means are required for effecting circulation of the hydrocarbons through the system. By controlling the level of hydrocarbons in 85 the containers 12, 13 and 14 it is possible to maintain a uniform quality of the asphaltic product discharged from the containers. It will be understood that the process of lifting hydrocarbons into a container by means of a gaseous 90 reagent can be repeated as often as necessary in order to obtain the desired quality of product. It will be understood that the hydrocarbon containing system can be operated under atmos- 95pheric pressure, less than atmospheric pressure, or under greater than atmospheric pressure.

Various changes may be made within the scope of the appended claims in which it is desired to claim all novelty inherent in the invention as broadly as the prior art permits.

I claim:

1. Apparatus for treating liquid hydrocarbons comprising a heating structure divided into a plurality of chambers by a series of walls, a vertically disposed still partially projecting 105 downwardly in each chamber, a feed conduit and a discharge conduit leading downwardly from each still through the heating chambers to a point outside of the heating chambers, connection between the discharge conduit of a still 110

and the feed conduit of the next still, means for leading off vapors from the top of each still, means for injecting gaseous materials into the feed conduits, means for removing liquid from the discharge conduits and means for controlling the liquid level in each still.

2. Process of continuously treating liquid hydrocarbons for the production of oxidized asphalts therefrom, oxidized to various degrees by treatment with a gaseous agent containing free oxygen, which comprises passing a liquid hydrocarbon while applying heat thereto upwardly

through a series of narrow elongated and substantially vertical treating zones and separating zones on their upper ends, discharging the hydrocarbons from each separating zone to the lower portion of the next narrow elongated treating zone, injecting the gaseous reagent containing free oxygen into the lower part of each narrow elongated treating zone, withdrawing gases and vapors from the upper portions of the separating zones and withdrawing at will oxidized asphalt from any of the separating zones.
